MEAT TENDERING MACHINE

Glenn W. Tamm, Park Ridge, Ill., assignor to
U. S. Slicing Machine Company, Inc., La Porte,
Ind., a corporation of Indiana

Application June 18, 1948, Serial No. 147,046

Term of patent 14 years

(Cl. D44—29)

To all whom it may concern:

Be it known that I, Glenn W. Tamm, a citizen of the United States, residing at Park Ridge, in the county of Cook and State of Illinois, have invented a new, original, and ornamental Design for Meat Tendering Machine, of which the following is a specification, reference being had to the accompanying drawings, forming a part thereof.

Fig. 1 is a perspective view of a meat tendering machine, showing the front of my new design.

Fig. 2 is a perspective view of a meat tendering machine showing the rear of my new design, the dominant features of which reside in those portions shown in full lines.

I claim:

The ornamental design for a meat tendering machine, as shown and described.

GLENN W. TAMMEN.
